CARL WINKLER, OF BERN, SWITZERLAND

AUTOMATIC DRIVE FOR OPENING AND CLOSING MOLD BOXES AND METAL-CONTROLLING ORGANS IN MACHINES FOR CASTING STEREOPLATES

Application filed May 10, 1928, Serial No. 276,764, and in Germany May 21, 1927.

Automatic drives for machines for casting stereo-plates already exist in which the shaft for closing the mold-box is driven from a continuously rotating part by means of 5 spur-wheels.

According to my invention the shaft by which the mold box is opened and the shaft by which the organ for controlling the flow of molten metal into the mold box is opened 10 and closed are operated by the continuously rotating part also through spur-wheel segments, but by means of mechanical elements which, in the working periods of said shaft are moved quickly by spur-wheels and spur- 15 wheel segments, and, in the time for cooling the cast plates, are moved slowly by means of a one-tooth wheel and spur-wheel segments.

The advantage of this device consists in the fact that one of two mechanical elements 20 driven at different speeds can be constructed as a hollow shaft on the shaft for operating the mold box, and the other mechanical element can be arranged as a hollow shaft on the shaft for operating the metal controlling 25 organ. As the continuously rotating part can also revolve loosely on one of the shafts, it is possible to arrange the whole drive on two shafts in a very compact manner.

In the accompanying drawing Fig. 1 shows 30 a horizontal section through the entire drive, Fig. 2 a section on A—B, Fig. 3 is a section on C—D and Fig. 4 a section on E—F in Fig. 1.

The shaft *a* serves for operating the organ (valve) for controlling the flow of molten 35 metal, and the shaft *b* for operating the mold box. On the shaft *a* is keyed the spur-wheel *c* and on the shaft *b* is keyed the spur-wheel segment *d*. The shaft *a* is surrounded by the hollow shafts *e*, *f*, of which *e* is one of 40 the parts termed mechanical elements in the above general description. The shaft *b* is surrounded by the hollow shaft *g*, the other mechanical element mentioned above. On the hollow shaft *f* is keyed the worm-wheel *h* that is driven continuously by a worm (Fig. 45) when the drive is put into operation to cast a plate. The rotation of the worm-wheel *h* is transferred by the hollow shaft *f* and spur-wheel segment *i* to the spur-wheel segment *d*, so that the shaft *b* is turned quickly until

the spur-wheel segments *i*, *d* come out of engagement with other. The mold box is then closed. During the rotation of the shaft *b* the shaft *a* is also turned at a slower speed by the spur-wheel *k*, spur-wheel segment *l*, 55 hollow shaft *g*, spur-wheel segment *m* and spur-wheel *c*. The shaft *a* continues this rotation until all the teeth of the spur-wheel segment *l* have passed out of engagement with the spur-wheel *k*, in which position 60 the metal controlling organ actuated by the shaft *a* is open. By this rotation of the hollow shaft *g* the teeth of another spur-wheel segment *n* secured on this shaft is brought into engagement with the one-tooth wheel *w* 65 fastened on the hollow-shaft *f*, which during each revolution turns the spur-wheel segment *n* through the angle of 3 teeth. In this period of slow rotation of the hollow shaft *g* this shaft is held between each turning 70 movement by a pawl *z* engaging in the disc *n'*. During this period the shafts *a*, *b* are stationary, because the teeth of the spur-wheel segments *i* and *m* are not in engagement with the teeth of the segment *d* and 75 spur-wheel *c*. This period of slow motion corresponds with the time required to cool 80 the plate, and the metal controlling organ remains open, and the mold box closed, until by the rotation of the hollow shaft *g* the teeth of the spur-wheel segment *l* come into 85 engagement with the spur-wheel *k* and the teeth of the spur-wheel segment *m* come into engagement with the spur-wheel *c*, whereupon the metal controlling organ is closed. 90 The rotation of the hollow shaft *g*, no matter whether this shaft is turning quicker or slower is transferred by the spur-wheels *o*, *p* to the hollow shaft *e*, so that during the slow motion of the hollow shaft *g* simultaneously the spur-wheel segment *q*, keyed on the hollow shaft *e*, is brought into engagement with the spur-wheel segment *r*, made in one piece with the spur-wheel segment *d*, whereupon the mold box is opened by the rotation of the hollow-shaft *e* when the hollow-shaft *g* is being turned by the spur-wheel *k* and spur-wheel segment *l*. This opening of the mold-box 95 takes place comparatively slowly because the diameter of the spur-wheel *k* is smaller than 100

that of the spur-wheel segment *l*, and the spur-wheels *o*, *p* have the same diameter.

The shaft *b*, in the position in which the mold box is closed, is locked by the discs *s*, *t* operating in the manner of a Geneva cross. Similar discs *u*, *v* and *y*, *z* are provided to lock the shaft *a* in the positions corresponding to the open and closed positions of the metal controlling organ.

10 What I claim and desire to secure by Letters Patent of the United States is:

1. An automatic drive for opening and closing the mold box and metal controlling organ in machines for casting stereo-plates, comprising in combination, a continuously rotating part, a shaft to operate the mold box, a shaft to operate the metal controlling organ, gearing to turn the shaft serving to operate the mold box to close said mold, a hollow shaft surrounding the shaft serving to operate the mold box and adapted to be turned by said continuously rotating part both quickly and slowly, means enabling said hollow shaft, when moving quickly, to turn the shaft for operating the metal controlling organ, a second hollow shaft surrounding the shaft for operating said metal controlling organ and adapted to be driven by said first hollow shaft, and means enabling said second hollow shaft to turn said shaft for operating the mold to open said mold, substantially as, and for the purpose, set forth.

2. An automatic drive for opening and closing the mold box and metal controlling organ in machines for casting stereo-plates, comprising in combination, a continuously rotating part, a shaft to operate the mold box, a shaft to operate the metal controlling organ, a hollowing shaft on the mold box organ, a pair of hollow shafts on the organ operating shaft, and gearing fixed to the hollow shaft and operable at predetermined times to rotate either the mold box shaft or the organ operating shaft.

3. An automatic drive for opening and closing the mold box and metal controlling organ in machines for casting stereo-plates, comprising in combination, a continuously rotating part, a shaft to operate the mold box, a shaft to operate the metal controlling organ, gearing to turn the shaft serving to operate the mold box to close said mold, a hollow shaft surrounding the shaft serving to operate the mold box and adapted to be turned by said continuously rotating part both quickly and slowly, means enabling said hollow shaft, when moving quickly, to turn the shaft for operating the metal controlling organ, a second hollow shaft surrounding the shaft for operating said metal controlling organ and adapted to be driven by said first hollow shaft, and means enabling said second hollow shaft to turn said shaft for operating the mold to open said mold, and means

for latching the first mentioned hollow shaft against rotation at predetermined times. In testimony whereof I have signed my name to this specification.

CARL WINKLER.
